UNITED STATES PATENT OFFICE.

HARRY ADAMS, OF THE UNITED STATES NAVY.

GAME APPARATUS.

1,368,875.

Specification of Letters Patent. Patented Feb. 15, 1921.

Application filed May 20, 1920. Serial No. 382,916.

To all whom it may concern:

Be it known that I, HARRY ADAMS, a citizen of the United States, of the United States Navy, have invented certain new and 5 useful Improvements in Game Apparatus; and I do hereby declare the following to be a full, clear, and exact description of the invention, such as will enable others skilled in the art to which it appertains to make and 10 use the same.

My invention relates to improvements in game apparatus of somewhat similar character to pool or billiards, and it comprises an apparatus constituting a board, a plurality of balls on said board, a plurality of pockets or indentations into which said balls are to be projected, and an impeller adapted to coöperate with one of said balls whereby other balls of the series may be 15 driven into the corresponding pockets or indentations.

In order to effect the operation of the cue ball I use, instead of an ordinary hand-operated cue, a mechanical impeller comprising 20 a lever provided with a weighted arm and a spring-returned plunger, adapted to be caused to strike said lever and throw the weighted arm into sudden contact with the cue ball, whereby sufficient velocity is imparted to the said ball to accomplish the results desired; the force of the blow imparted 25 to the ball being dependent upon the nature of the blow applied to the plunger.

My invention will be more fully understood after reference to the accompanying drawings, in which like parts are indicated by similar reference symbols throughout the several views, and in which:—

Figure 1 is a plan view of the board constructed according to my invention and showing 15 balls in addition to the cue ball, with a number of recesses into which said balls are to be impelled, together with a view of the impeller resting on said table.

Fig. 2 shows a section along the line 2—2 of Fig. 1, and looking in the direction of the arrows.

Fig. 3 shows a section along the line 3—3 of Fig. 1, and looking in the direction of the arrows.

Fig. 4 is a side elevation of the impeller in the distended position.

Fig. 5 shows a central section through the impeller of Fig. 4, the lever carrying the

weighted arm being shown in elevation, and 55 the ball about to be struck being shown in dotted lines.

Fig. 6 is a similar view to Fig. 5, but shows the plunger in the lowered or operative position with the ball started on its 60 flight; and

Fig. 7 is a view of one of the balls used in the apparatus.

A represents a table having the usual pockets a at the corners and sides thereof, 65 being generally similar, but on a smaller scale, to the ordinary 15-ball pool table. This table may be provided with grooves a' at each end thereof to receive the balls B after the same have been pocketed. The 70 balls are shown in these grooves or racks in full lines, and their pyramidal arrangement on the table is shown in dotted lines. The table may be also provided with the usual spots a^2 for the initial position of the cue 75 ball, and a^3 for the initial position of the number one ball of the pyramid.

B' represents the cue ball, which may be of special design or color, or generally similar to the other balls. 80

E represents the impeller or operating device adapted to take the place of the ordinary cue ball used in pool or billiards, or the mallet used with croquet or similar games. This impeller comprises a heel member E' provided with the pin e on which the lever F is pivoted. This lever has a short operating arm f and a weighted arm f'. The heel member E' is provided with a spline groove e^0 in which projects a guide 90 pin e' of the plunger sleeve E², which plunger sleeve is preferably made in tubular form and contains a return spring H.

This sleeve E² is preferably provided with an air vent e^2 to prevent excessive cushioning effect of the air therein. 95

The complete apparatus for a miniature pool game is indicated in Fig. 1.

In order to use the device to play miniature pool, up-end the impeller and move it 100 with the weighted arm f' close against the cue ball, as shown in Fig. 5; then a sudden blow on the top of the sleeve E² will cause the lower end of said sleeve to strike the arm f of the lever F, imparting a quick 105 movement to the weighted arm f' and throwing the ball outward. The force of the blow imparted to the ball will, of course, depend

upon the nature of the blow imparted to the impeller lever. If gentle movement is desired a light blow only may be given to the sleeve E^2 , while if a stronger shot is desired 5 the blow would, of course, be harder. The direction of the initial path of the ball can be determined by properly positioning the weighted arm f' .

It will be obvious that considerable dexterity 10 may be obtained after practice in imparting the proper velocity to the ball, or in starting the ball in the proper direction.

While I have shown the invention as applied 15 to propelling balls on a table, for instance in apparatus for playing 15-ball pool in miniature, it will be obvious that the impellers may be used for playing billiards on a miniature scale and used to impel balls on a lawn, as in miniature croquet, golf, or the like; the idea being that the ball is struck by 20 a weighted arm and impelled in the desired direction and that the velocity imparted to the ball will depend upon the nature of the blow imparted to the implement itself and 25 transmitted by it to the ball.

It will be obvious that various modifications 30 might be made in the herein described apparatus, and in the construction, combination and arrangement of parts which could be used without departing from the spirit of my invention; and I do not mean to limit 35 the invention to such details except as particularly pointed out in the claims.

Having thus described my invention what

I claim and desire to secure by Letters Pat- 35 ent of the United States is:—

1. Game apparatus comprising a table, a plurality of balls, and an impeller having a heel piece, a lever pivoted to said heel piece and having a striking arm adapted to strike 40 the ball, and a hollow plunger slidably mounted on said heel piece and adapted to operate said lever.

2. Game apparatus comprising a table, a plurality of balls, and an impeller having a 45 heel piece, a lever pivoted to said heel piece and having a striking arm adapted to strike the ball, and a hollow plunger slidably mounted on said heel piece and adapted to operate said lever, with a return spring 50 mounted in said hollow plunger.

3. An impeller for use in game apparatus of the character described, comprising a heel piece, a hollow plunger slidably mounted thereon, and a bell crank lever pivoted to 55 said heel piece and having an arm adapted to engage said plunger, and a second arm adapted to strike the ball.

4. An impeller for use in game apparatus of the character described, comprising a heel 60 piece, a hollow plunger slidably mounted thereon, a return spring inclosed in said plunger, and a bell crank lever pivoted to said heel piece and having an arm adapted to engage said plunger, and a second arm 65 adapted to strike the ball.

HARRY ADAMS.
